CLAIM

The ornamental design for an utility vehicle, as shown and described.

DESCRIPTION

FIG. 1 is a front elevational view of an utility vehicle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a front and right-side isometric view thereof; and, FIG. 7 is a rear and right-side isometric view thereof.

The dark and light grayed surfaces do not represent a color nor a pattern but are intended to represent shading on the surface of the drawings. The features on the Drawings formed in the white overlay wash form no part of the claimed design.
